UNITED STATES PATENT OFFICE.

BARTHOLOMEW J. MORRISON, OF NEW YORK, N. Y., ASSIGNOR TO EDWARD R. DUNHAM, OF NEW YORK, N. Y.

GRATE-BAR FOR CHAIN-GRATE STOKERS.

1,146,198.

Specification of Letters Patent. Patented July 13, 1915.

Application filed March 10, 1914. Serial No. 823,661.

To all whom it may concern:

Be it known that I, BARTHOLOMEW J. MORRISON, a citizen of the United States, and a resident of New York city, in the county of

5 New York and State of New York, have invented certain new and useful Improvements in Grate-Bars for Chain-Grate Stokers, of which the following is a specification.

10 This invention relates to mechanical stokers, particularly of the chain grate type. It is often found necessary in a stoker of this character to remove one of the grate bars for the purpose of replacement or

15 repair. To accomplish this, it has hitherto been found necessary to practically dismantle the entire grate. Also when one of the grate bars is burnt at one point, it has usually been necessary to throw the entire

20 bar away.

The principal objects of the present invention are to avoid these difficulties and to this end I provide a sectional grate bar, the parts of which are normally coupled rigidly together, the coupling being readily accessible for detaching the sections, whereupon the latter are readily swung out without disturbing the chains or the other grate bars.

25 The various further objects and advantages will appear more fully from the following detailed description and the features of novelty in the construction and combination of parts will be clearly pointed out in the claims.

30 In the drawings illustrating this invention, Figure 1 is a sectional elevation of a chain grate stoker located in the fire box of a steam boiler, with the grate bars of the improved construction applied thereto.

35 Fig. 2 is a detail elevation of a grate bar detached illustrated as engaging the links of the chain. Fig. 3 is a bottom view of the grate bar shown in Fig. 2, and Fig. 4 is a section taken along line 4-4 of Fig. 2.

40 Fig. 5 illustrates a modified form in which the grate bar is made in three sections. Fig. 6 is a fragmental elevation, and Fig. 7 is a fragmental plan view of a further modified form in which the hook portions alone

45 are detachable. Fig. 8 is a section taken along line 8-8 of Fig. 1, illustrating the manner in which the bars may be removed from the chains.

50 Referring in detail to Figs. 1, 2, 3, 4 and 8 of the drawings, the chain grate consists of a

pair of endless chains 10, passing over the opposing sprocket wheels 11 and 12. Through these sprockets the chains are actuated to feed the coal forward, as will be readily understood by those skilled in the art.

55 Carried by the links of the chain are the grate bars, which according to my improved construction, are readily detachable individually without disturbing the chains or the other grate bars. Each grate bar is 60 formed in two sections 13 and 14, each of which may be stiffened with the usual depending webs 15 and 16. The sections are locked or coupled rigidly together by a pin 17, which passes through registering apertures in the ears 18, extending from the web 15, and an aperture in the body of the web portion 16, which is embraced by the ears 18. The latter form a fork in which the mating portion of the web 16 lodges and together therewith constitute three registering 65 ears into which the pin or key 17 is driven 70 to firmly unite the sections of the grate bar.

75 For engaging the links of the chain, each section is provided at its outer end with an 80 upturned hook projection 19 which hooks into the vertical links of the chains. Thus, when a grate bar is to be removed, the driving sprocket is turned until the particular 85 grate bar is in the position of the grate bar which is viewed in the direction of the arrows in the section line 8-8 of Fig. 1. Referring to Figs. 1 and 8, it will be noted that the pin 17 may be readily reached and removed by inserting a tool between the grate 90 bar in question and the adjacent grate bar and then the sections may be swung out as indicated in dotted lines in Fig. 8. By reason of the hooked formation of the projections 19, this swinging action may be readily 95 accomplished without disturbing the chains. To facilitate the swinging action the hook projections are preferably formed with substantially arcuate outer surfaces 20.

100 When a new grate bar is to be inserted, the reverse of the above operation is gone through. The sections are swung into place from the position indicated in dotted lines to the position indicated in full lines in Fig. 8, and the locking key is driven into the registering ears by a suitable tool.

105 In the modified construction illustrated in Fig. 5, the grate bar is formed in three sections consisting of a body portion 23 and separate end portions 24 and 24^a. These sec- 110

tions are united by locking pins 27 passing through registering ears formed upon the adjacent sections as in the other form described. The end sections are also formed 5 with the upturned hook projections 29 which engage the vertical links in the chains 10.

In the further modified form illustrated in Figs. 6 and 7, the grate bar 33 has the detachable hook sections 34, each of which 10 is formed preferably with two upturned hook portions 39 engaging alternate links, as clearly indicated in Fig. 7. The detachable sections are preferably formed with the ears 38 which embrace the web 35 of the 15 grate bar and are coupled thereto by locking pins or keys 37.

From the various embodiments of my invention, it will be clear that I have provided a sectional grate bar for chain grate stokers 20 which may be readily inserted and removed from the chains without dismantling the chains or the other coöperating parts of the stoker. If one of the sections becomes burnt, it may be removed and replaced without necessitating the replacement of an entire 25 grate bar. Thus, the facility of repairing the stoker is increased and the cost of maintenance considerably reduced.

Having thus described my invention, I 30 claim as new and desire to secure by Letters Patent:

1. In a chain grate stoker, a grate bar comprising a plurality of sections detachably secured to each other, projections extending 35 from the outer ends of the sections, said projections interlocking with the chains and serving as suspending means for the grate bar, and said sections when detached from each other while in their inverted position being adapted to be swung transversely of the chains out of engagement therewith.

2. In combination with a pair of traveling chains of a chain grate stoker, of a sectional 45 grate bar having projections for engaging the vertical links of the chain, and means for uniting the sections to form a rigid bar, said sections when detached from each other being adapted to be swung transversely of the chains out of engagement therewith.

3. A grate bar for chain grate stokers consisting of a plurality of sections, means for locking the sections to each other and hooked projections at the outer ends of the sections for engaging the vertical links of the chains, said hooked projections being adapted to be swung transversely of the chains out of engagement therewith when the sections are unlocked. 55

4. A grate bar for chain grate stokers consisting of a plurality of sections, means for locking the sections to each other and upturned hooked projections at the outer ends of the sections for engaging the vertical links 65 of the chains, said hooked projections being adapted to be swung out of engagement with the chains when the sections are unlocked. 60

5. A grate bar for chain grate stokers consisting of a plurality of sections, each section comprising a body portion, a web for supporting and stiffening the body, registering ears on the meeting ends of the web portions, a key passing through said ears 75 to lock the sections together, and hooks formed on the outer ends of the grate sections for engaging the chains, the sections being adapted to swing out of engagement with the chains when the sections are unlocked from each other. 80

6. In combination with the driving sprocket and chains of a chain grate stoker, of a sectional grate bar comprising a body portion for supporting the fuel and a stiffening web formed at the bottom of the body portion transverse thereto, hooked projections formed on the outer ends of the sections adapted to engage the chains, registering ears formed on the extremity of the web 90 and the adjacent section, and a key passing through the ears for locking the sections together, said key being exposed for separating the sections when the bar passes over the driving sprocket. 95

Signed at New York city, in the county of New York, and State of New York, this 3rd day of March A. D. 1914.

BARTHLOMEW J. MORRISON.
